INVENTOR

EUGENE MCLEAN LONG

BY

O. E. Edwards

ATTORNEY

UNITED STATES PATENT OFFICE.

EUGENE McLEAN LONG, OF PORT WASHINGTON, NEW YORK.

KEY HOLDER.

Application filed March 8, 1926. Serial No. 93,013.

The object of my invention is to provide a key holder in which keys may be easily inserted or removed and in which such keys may be folded when not in use so as to be out of the way, as the blade of a knife may be folded in the handle when out of use. This object is accomplished by my invention, some embodiments of which are herein-after more particularly set forth.

For a more detailed description of my invention, reference is to be had to the accompanying drawings, forming a part hereof, in which—

Figure 1 is a plan view of a key holder embodying my invention.

Figure 2 is a side elevation of the same.

Figure 3 is a sectional view, taken on the line 3—3 of Figure 2, except that the section shows all keys in the folded in position.

Figure 4 is a perspective view of the holder without any keys, and Figures 5 and 6 show modified structures.

Throughout the various views of the drawings, similar reference characters designate similar parts.

My improved holder 1 is composed of a spring metal band 2 with reduced ends 3 which overlap and are adapted to fit with a loose fit in the perforations 4 of keys 5 so that the keys may be turned on the projections 3, as pivots.

The band 2 also has indentations 6 which register with corresponding slots 7 in the keys 5 so as to hold the keys in their closed positions when in the band 2.

When my key holder is in use, the ends 3 are first sprung apart and keys 5 inserted, as indicated. These keys are preferably of the flat type, such as are in common use.

When inserted, these keys may be turned so that their shanks are folded into the holder 1, as indicated in Figure 3, or one or more of these keys may be turned so that the shank is free of the holder, as indicated in Figures 1 and 2, and then a key may be used to lock or unlock a door.

In the modification shown in Figure 5, the end 8 is composed of two surfaces which meet in the center to form a dihedral angle and the sides 9 converge and then run parallel, as indicated, so that keys may be held in place by a frictional grip only. In this embodiment of my invention, the dents 6 are unnecessary as the keys are held without them.

In the modifications shown in Figure 6, the end 10 is a block of any suitable kind and it preferably has inclined ends, as shown, on which are mounted the sides 9 which converge in the manner above described and are held in place by rivets 11 which pass through them and the block. In this embodiment of my invention, the keys are held by rivets 12 placed at the open ends of the sides 9 which rivets overlap in substantially the same manner as the integral ends 3 in Figures 4 and 5. In this embodiment, the keys are held as in the structure of Figure 5.

While I have shown and described one embodiment of my invention, it is obvious that it is not restricted thereto, but that it is broad enough to cover all structures that come within the scope of the annexed claims.

Having thus described my invention, what I claim is:

1. A key holder composed of an end, two converging spring sides and overlapping parts adapted to pass through the openings in keys and hold the same in place, the sides being so arranged and disposed that they will grip the keys and hold them with a frictional contact.

2. A key holder formed by two flat springs symmetrically placed with regard to each other joined rigidly at one end with the other ends free and pressed towards each other so that they will grip a key or any other object placed between them.

In testimony whereof, I have hereunto set my hand this 6th day of March, 1926.

EUGENE McLEAN LONG.
